(57) **CLAIM**

The ornamental design for an electric rotary actuator, as shown and described.

DESCRIPTION

1. Electric rotary actuator
  - 1.1 : bottom in rear right perspective
  - 1.2 : bottom in rear centered perspective
  - 1.3 : bottom in rear left perspective
  - 1.4 : top view, front left perspective
  - 1.5 : top view, front right perspective
  - 1.6 : top view, front centered perspective
